Application June 26, 1931, Serial No. 547,031
In Germany July 27, 1925

6 Claims. (Cl. 196—23)

This application is a continuation-in-part of the application for Letters Patent Ser. No. 123,030, filed July 16, 1926.

The present invention relates to a method for refining crude liquid hydrocarbons rich in hydrogen with a view to removing therefrom impurities diminishing the value of said liquid hydrocarbons, as for example, resinous bodies, asphalts, highly unsaturated hydrocarbons of high molecular weight or like bodies poor in hydrogen or substances poor in hydrogen containing oxygen as for example, phenols or acids, or sulphur.

We have found that crude liquid hydrocarbons rich in hydrogen can be purified with great advantage by washing them with a mixture comprising methanol and cyclic hydrocarbons of low boiling point, for example, boiling below 100° C. Said cyclic hydrocarbons may belong to the aromatic or hydroaromatic series and benzene 10 and its homologues, such as toluene or xylene, or cyclohexane and its homologues may be employed with particular advantage as admixtures to the methanol to form the washing agent.

By "washing" we understand extracting or dissolving out the impurities from the crude liquid hydrocarbons, while the bulk of said hydrocarbons remains undissolved.

The new process is particularly applicable to the purification of crude hydrocarbon oils, boiling wholly or for the most part, say to the extent of more than 90 per cent, above 325° C., which are rich in hydrogen and which contain, for example, more than 13, and preferably more than 13½, parts of hydrogen for each 100 parts of carbon. Such hydrocarbons will usually have an average molecular weight of 300 to 400 or more. As examples of the crude hydrocarbons, which may be refined with advantage in accordance with the present invention may be mentioned 30 crude lubricating oils, primary tar, the high boiling crude fractions of destructive hydrogenation products, crude mineral oil fractions rich in hydrogen, fractions of low temperature carbonization tar and preferably fractions of the said 35 hydrocarbons boiling above 325° C. The crude hydrocarbons to be purified are preferably of paraffinic or naphthenic nature.

The washing liquid should preferably contain at least 2 parts by volume of methanol for each 50 part by volume of the cyclic hydrocarbon employed and usually washing liquids containing between 3 and 5 parts by volume of methanol for each part of cyclic hydrocarbon will give good results in practice. Even more methanol may 55 be present in the said washing liquids and the

proportion may be for example 8 parts by volume of methanol to 1 part by volume of the cyclic hydrocarbon. The cyclic hydrocarbon appears to exercise the function of a solvent intermediary, since to a certain degree the separating action is 60 improved, if larger amounts of methanol are contained in the washing mixture, but, if the amount of methanol is increased too much the separating action is greatly impeded, since not enough cyclic hydrocarbon is then present to enable it to exercise its beneficial function. The methanol may be either natural or synthetic.

The amount of washing liquid employed may be varied in a wide degree but good results are obtained in practice by working with 1 part or 70 more of washing liquid for each part of crude hydrocarbon to be refined.

The washing treatment may be carried out at any suitable temperature, but good results are obtained in practice by working at about 15° C. 75 or somewhat higher, for example, at 30° C. If higher temperatures, as for example a temperature of 60° C., be employed it may be advantageous to carry out the washing operation under pressure as otherwise a considerable volatilization of the washing liquid is liable to occur.

Prior to the washing treatment, it may be advantageous to separate solid paraffins from the crude hydrocarbon oils, for example, by cooling to low temperatures and removing the paraffin 85 wax separated by filter pressing or centrifuging.

The washing operation is preferably carried out in a continuous manner and advantageously by counter-current washing. If the crude oil has a higher specific gravity than the washing 90 liquid, when working in counter-current it is preferably introduced at the top of the washing apparatus and the washing liquid at the bottom of the said apparatus, whereas if the washing liquid has a higher specific gravity than the oil the opposite method of procedure is adapted. For the counter-current washing operation it is 95 advantageous to employ a high tower or column.

How the invention may be carried out in practice will be further illustrated with reference to the accompanying drawing, which shows diagrammatically in elevation and partly in section apparatus which may be employed in the said process with particular advantage but it should be understood that the invention is not limited to operations carried out in the said apparatus.

Referring to the drawing A is a container for crude liquid hydrocarbon mixture to be refined, B is a line provided with the valve B₁ through 110

which said crude liquid hydrocarbon mixture is passed to the regulating booster C. Said booster passes the hydrocarbon through line E to the point F where it enters into the washing tower K. G. 5 is a container for washing liquid which is passed through line H and valve H₁ by means of the regulating booster D to the point J where it is introduced into the bottom of the washing tower K. The washing liquid passes upwards in the 10 tower whereas the crude hydrocarbon undergoing treatment passes downwards. A surface of separation forms at K₁ and the position of the said surface is maintained constant by suitable regulation of the rate of working of the boosters 15 C and D. The column is preferably filled with distributing materials, such as lumps of burnt fire-clay, Raschig rings and the like. The washed hydrocarbon issues from the tower through valve L and is passed by way of line M 20 to the middle of the distillation column N. The said column N is heated by the coil N₁ arranged in the lower part thereof to which hot flue gases are introduced from X through line N₁. The cold flue gases pass off from the said coil at Z. 25 The upper part of the said column N is cooled by the coil N₂, cooling water being introduced at P₁ and withdrawn at P. In the said column any washing liquid contained in the washed hydrocarbon is expelled and passes off by way of line 30 Q to the condenser R. The washing liquid thus recovered is returned to the container G by way of line R₁. The washing liquid containing the impurities removed from the crude hydrocarbon passes off from the tower K through valve 35 W₁ and is introduced into the middle part of the distillation column O at W. Said distillation column O is heated by the coil O₁ to which hot flue gases are introduced through valve X₁ and withdrawn through valve X₂. In the other 40 part of said distillation column a cooling coil O₂ is contained to which water is introduced at P₂ and removed at P₃. The washing liquid thus recovered passes off from the tower O at S to the condenser R and is thence returned by way 45 of line R₂ to the container G. In addition to or instead of the indirect heating by hot flue gases of the distillation columns N and O, hot nitrogen may be introduced from U into the said towers through the valves V and V₁. The refined hydrocarbon oil is withdrawn from the bottom of 50 the distillation column N by way of the pipe T and may be passed to storage or to a place where it may be employed. The impurities recovered from the washing liquids are withdrawn from 55 the bottom of the column O by way of line Y.

The following examples will further illustrate how the invention may be carried out in practice but it should be understood that the invention is not limited to the said examples.

60

Example 1

Referring to the drawing, a washing liquid consisting of a mixture of 1 part by volume of cyclohexane and 4 parts by volume of methanol was introduced into the container G and a crude Columbian lube distillate into the tank O the boosters C and D were operated at such a rate that the amount by volume of washing liquid present at any time in the tower K was twice 65 that of the amount of lube distillate present. The washed lube distillate containing a little of the washing liquid was drawn off continuously from the tower K through valve L and passed into the distillation column N. The refined 70 product was drawn off at T. In the washing tow-

er a temperature of about 30° C. was maintained. The impurities washed out pass off from the distillation column O through line Y and the washing liquid passes off at S and after condensation in the condenser R is returned to the tank G. The following table shows the improvement of the oil in the process according to this example

	Initial oil	Refined product	80
Specific gravity	0.922	0.912.	
Viscosity at 38° C.	44.9	39.82.	
Viscosity at 90° C.	2.50	2.58.	
Viscosity index	40	52.	
Color	Dark greenish-brown; opaque.	Yellowish-green; translucent.	
Yield		88 to 90 percent by weight.	90

Example 2

A different crude Columbian lube distillate was 95 treated in the manner described in Example 1. The results obtained were as follows:

	Initial oil	Refined product	100
Specific gravity	0.914	0.902.	
Viscosity at 38° C.	17.0	16.7.	
Viscosity at 90° C.	1.86	1.89.	
Viscosity index	30	52.	
Color	Dark, greenish-brown; opaque.	Yellowish-green; translucent.	
Yield		80 to 85 percent by weight.	105

Example 3

A residue resulting from the distillation of destructively hydrogenated brown coal producer 110 tar (that is brown coal producer tar, which has been subjected to treatment with hydrogen or gases giving off hydrogen at elevated temperature with or without the aid of elevated pressure or catalysts or both and this has been converted 115 into more valuable organic products) is washed in a counter-current in the manner above described with a mixture of 1 part, by volume, of benzene and between 4 and 5 parts, by volume, of 120 methanol. From the bottom of the column or 125 tower, a nearly colorless oil is withdrawn which has the character of a mineral oil and can be employed, for example, as lubricating oil. It is obtained in a yield of about 40 to 50 per cent of the crude distillation residue. The mixture of 125 methanol and benzene removed at the upper end of the tower or column contains all tarry and other impurities of the crude residue and may be separated by distillation.

Example 4

A high boiling fraction of a crude German mineral oil is washed in the manner described in the foregoing example. Thereby the impurities contained in the crude product in an amount 135 of about 10 to 15 per cent thereof are removed. The refined product is a valuable lubricating oil free from asphalt.

What we claim is:—

1. The process of refining a crude liquid hydrocarbon, boiling to the extent of at least 90 per cent above 325° C. and containing more than 13.0 per cent of hydrogen for each 100 parts of carbon, which comprises washing said hydrocarbon with a mixture of methanol and a hydro- 145 aromatic hydrocarbon of low boiling point.
2. The process of refining a crude liquid hydrocarbon, boiling to the extent of at least 90 per cent above 325° C. and containing more than 13.0 per cent of hydrogen for each 100 parts of 150

carbon, which comprises washing said hydrocarbon with a mixture of methanol and cyclohexane.	5. The process of refining a crude liquid hydrocarbon boiling to the extent of at least 90 per cent above 325° C. and containing more than 13.0 per cent of hydrogen for each 100 parts of carbon which comprises washing said crude liquid hydrocarbon continuously in counter-current with at least an equal amount of a mixture of at least one part of methanol for each part of cyclohexane.	80
3. The process of refining a crude liquid hydrocarbon boiling to the extent of at least 90 per cent above 325° C. and containing more than 13.0 per cent of hydrogen for each 100 parts of carbon which comprises washing said crude liquid hydrocarbon with at least an equal amount of a mixture of methanol and a hydroaromatic hydrocarbon of low boiling point.	6. A process for refining a crude lubricating oil, which comprises washing said lubricating oil at a temperature of about 30° C. in counter-current with about twice the amount, by volume, of a mixture of about 4 parts of methanol and one part of cyclohexane.	85
10 mixture of methanol and a hydroaromatic hydrocarbon of low boiling point.	CARL KRAUCH. MATHIAS PIER. AUGUST EISENHUT.	90
